UNITED STATES PATENT OFFICE.

GEORGE WILLIAM MULLINS AND GRAHAM SQUIERS, OF BIRMINGHAM, ENGLAND.

SURFACE OF ROOFS, WALLS, DOORS, PANELS, AND OTHER PARTS OF BUILDINGS AND STRUCTURES.

Application filed March 28, 1927, Serial No. 178,919, and in Great Britain July 31, 1926.

The invention relates to roofs, walls, doors, panels and like parts of buildings and structures, and provides for the weather-proofing of their surfaces as will be herein-after described.

A weather-proof surface according to the invention comprises a plurality of boards fixed the one above the other horizontally so that the lower edge of each board forms a longitudinal ridge, and a plurality of strips of thin metal such as copper laid horizontally the one above the other along and over said boards to make weather-tight joint with each other at each ridge.

15 It is a part of the invention to have a double seamed joint of the longitudinal edges of the metal strips at or adjacent the ridge, and in making the joint to cover the nails whereby this joint is secured to the 20 ridge.

The boards are what are known as feather-edge boards, and the lower and thicker edge of the one may abut against the upper and thin edge of the board below either with 25 a butt joint, or with an overlapping joint, or with a rabbeted joint, so long as the ridge is provided to step the boards down the one below the other. The metal strips have 30 their seamed joints made so as to fold and lie closely against the thickest edge of the boards at the ridge formed by said thickest edge.

The joints of the strips of thin metal may be made in situ, or may be partly formed 35 previous to the strips being applied to the boards.

The invention is illustrated by the accompanying sheets of drawings, and will be particularly described in connection therewith.

40 Fig. 1 is a perspective section on a large scale of a portion of a surface according to the invention.

Fig. 2 is a perspective view on a smaller scale than Fig. 1 showing the first stage of 45 laying a strip.

Fig. 3 is a similar view to Fig. 2 showing the second stage of laying said strip.

Fig. 4 is a similar view to Figs. 2 and 3 showing the third stage of laying said strip.

50 Fig. 5 is a similar view to Fig. 4 showing the completed stage of laying said strip and the commencement of the laying of a fresh strip.

The structure to be surfaced, for instance 55 a roof, is covered in by a number of boards

a fixed the one above the other horizontally to supports (not shown in the drawings) such, for example, as battens of a roof. Said boards taper in thickness, and are closely applied so that the thicker lower edge *a*² 60 of the one board fits closely to the thin upper edge *a*³ of the adjacent board, providing between each two boards a step *a*⁴ forming a longitudinal ridge. These boards are what are known as feather-edge boarding, the thin edge of the one fitting closely to the thick edge of the other, so that in the surface there is a succession of cross-sectionally tapering boards put together for providing a succession of longitudinal steps *a*⁴ 70 forming ridges.

The boards *a* are now covered in by thin strip metal, preferably copper on account of its extreme flexibility, a strip for each board, with seamed joints between the strips folded to lie closely against or under the ridges.

75 Figs. 2-5 show a strip *c* applied to the lowest board in the elevated succession of boards, as the laying of the strips is commenced at the lowest board. This strip *c* 80 extends for the full length of the boards, as does every strip, and may be nailed at its lower edge *c*² to the lowest board, and is then bent at its upper edge against the step of the board above to form a deep flange *c*³.

85 The laying of the next strip *d* is now commenced, and firstly said strip is turned over and its one edge *d*² is bent at right-angles into a short flange and applied to the step of the board above against the deep flange 90 *c*³ of the strip *c*, these two bendings being now nailed to the step, as indicated at *e*, which is the first step of laying the second strip *d*. The deep flange *c*³ is now bent

95 downwardly over the short flange *d*² as represented at *f* in Fig. 5, after which the strip *d* is bodily lifted and bent upwardly about the two flanges *c*³, *d*², as represented by Figs. 3 and 4, so as to provide at the joint between the two strips *c* and *d* a double 100 seaming lying closely against the step *a*⁴ forming the ridge. The upper edge of this strip *d* is now bent against the succeeding upper step *a*⁴ with a deep flange *d*³ as represented by Fig. 4, after which a further 105

strip *g* is applied to the flange *d*³ and step, and to the upper board, in exactly the same manner as described with reference to the strip *d* in relation to the lowest strip *c*; this 110 succession of laying strips the one above the

other being continued to the uppermost board of the surface the strip for which may be ultimately secured in a similar manner to the securing of the strip *c* to the lowest board.

The drawings clearly show by Fig. 1 the joint between the two strips as finished and nailed to a step with the strip laid along and over the ridge, while Figs. 2-5 show

10 the different stages of applying the strips, the jointings being made in situ, but it will be obvious that parts of the joints may be formed before the strips are applied, as, for example, the short and deep flanges *c*³, *d*².

15 It will be seen from Figs. 1-5 that at the double seaming joint there are engaging hook formations providing four thicknesses of metal smashed down against a step in abutting relation thereto.

20 It is understood that there is a metal strip for each board, and that each board provides a ridge, and that the joint is at or adjacent the ridge, and that instead of the boards being close to each other vertically

25 they may be a distance apart, as, for instance, where the roof is not boarded all over, so long as the series of steps and ridges already described are provided, and so long as the overlapping edges form the folded

30 joints along the thicker edges of the boards.

The invention described for the surfacing of a roof is equally applicable to a wall or to a door, or to a panel, or to any part of a building or surface which is desired to be 35 weather-proofed, and the invention is not to be limited to wood as boards, or to copper as the covering strip, as thin strips of brass, bronze, lead, zinc or iron and steel may be used as the covering strip so long as the 40 covering is rendered weather-proof and rust-proof and is combined at the thick edges of the boards, namely at the ridges, to provide close and efficient joints.

Having now described our invention what 45 we claim and desire to secure by Letters Patent is:—

1. In a weather-proof surface, the combination with a plurality of boards tapered in cross-section and fixed one above the other horizontally so that the wider edge of each 50 board abuts against the narrow edge of an adjacent board to form a longitudinal ridge extending at right angles to the plane of the structure to which the surface is applied; of a strip for each board with the strip of 55 one board bent at right angles to the plane of the strip to form a flange which abuts against said ridge in a plane therewith, and the strip of a next adjacent board being also bent at right angles to the plane of the strip 60 to form a second flange engaging the first named flange also in a plane with said ridge, the remainder of the second strip being bent to extend along the upper surface of said 65 adjacent board.

2. In a weather-proof surface, the combination with a plurality of boards tapered in cross-section and fixed one above the other horizontally so that the wider edge of each 70 board abuts against the narrow edge of an adjacent board to form a longitudinal ridge extending at right angles to the plane of the structure to which the surface is applied; of a strip for each board with the strip of one 75 board bent at right angles to the plane of the strip to form a deep flange which abuts against said ridge in a plane therewith and the strip of a next adjacent board being also bent at right angles to the plane of the strip to form a relatively narrow flange 80 engaging the first named flange also in a plane with said ridge with a portion of the first named flange extending beyond the free edge of the second named flange and bent over the same to provide a triple thickness of 85 material along said ridge, the remainder of the second strip being bent to extend along the upper surface of said adjacent board.

In testimony whereof we have hereunto set our hands.

GEORGE WILLIAM MULLINS.
GRAHAM SQUIERS.
